UNITED STATES PATENT OFFICE

166,060

NECKTIE DISPLAY SUPPORT OR SIMILAR ARTICLE

Morris Aron, South Norwalk, Conn.

Application June 29, 1950, Serial No. 10,839

Term of patent 14 years

(Cl. D80—9)

To all whom it may concern:

Be it known that I, Morris Aron, a citizen of the United States and a resident of South Norwalk, Connecticut, have invented a new, original, and ornamental Design for Necktie Display Support or Similar Article, of which the following is a specification, reference being had to the accompanying drawing, forming a part hereof, in which

Figure 1 is a perspective view of a necktie display support or similar article, showing my new design; and

The dominant features of my design reside in the portion shown in full lines.

I claim:

The ornamental design for a necktie display support or similar article, as shown and described.

MORRIS ARON.
